CLAIM

The ornamental design for a shoe, as shown and described.

DESCRIPTION

FIG. 1 is a perspective view of a shoe, showing my new design.

FIG. 2 is left side view of the shoe shown in FIG. 1.

FIG. 3 is a right side view of the shoe shown in FIG. 1.

FIG. 4 is a top view of the shoe shown in FIG. 1.

FIG. 5 is a front view of the shoe shown in FIG. 1; and,

FIG. 6 is a rear view of the shoe shown in FIG. 1. The broken lines in the drawings illustrate portions of the shoe that form no part of the claimed design.

1 Claim, 5 Drawing SheetsFIG. 1

FIG. 4
